(57) **CLAIM**

An ornamental design for a shoe, as shown and described.

DESCRIPTION

FIG. 1 is a perspective view of a shoe;
 FIG. 2 is a front view of the shoe;
 FIG. 3 is a back view of the shoe;
 FIG. 4 is a side view of the shoe from an outside edge of the shoe;
 FIG. 5 is a side view of the shoe from an inside edge of the shoe; and,
 FIG. 6 is a top view of the shoe.
 The phantom lines showing portions of a shoe in FIGS. 1-6 are for illustrative purposes only and form no part of the claimed design.
